GAME BOARD

Robert L. Robbins, Jr., Berkeley, Calif., assignor
to Gordon L. Byers, Berkeley, Calif., as trustee

Application April 15, 1950, Serial No. 156,183

4 Claims. (Cl. 273—134)

1

The present game is called Mo-Chee-La, which is a coined adaptation of the Spanish word "Mochila," meaning a mantle for the saddle. Back in the days of the pony express, the mochila was an outer leather covering, draped over the saddle and secured only at the center front and back where the pommel and the cantle projected through reinforced holes fashioned to fit. The weight of the rider held it in place.

At each of the four corners of the mochila was fastened permanently a leather pouch or "Cantina" and into the pouch was placed a packet of mail to be carried overland. The flap of the cantina was sealed by a United States postmaster at the start of the trip, such as St. Joseph, Missouri, and it was not opened until the destination of the trip was reached, such as San Francisco, California. As one relay ended and another began, the mochila was lifted from the saddle of the incoming rider and placed over that of the outgoing rider. The exchange was measured by seconds.

The mechanics of Mo-Chee-La are based on the pony express which required several hundred horses; one hundred and ninety stock stations for changing the riding stock; two hundred station tenders to care for the horses and have them ready for the incoming riders to mount; and eighty riders with stations supplied with feed for the horses and other needed materials. It required \$100,000.00 in gold coin to establish and equip the line.

The game of Mo-Chee-La is in reality two games in one; the first one being called Rider Round-Up, and the second being called Carrying the Mail. Both are played on a foldable playing board and the instruments of play are reminiscent of the Old West and pioneer days; such as cards, poker chips, gold nuggets, the poke and the paymaster. The game is designed for four players and the object of each player is to amass the greatest wealth.

Other objects and advantages will appear in the following specification, and the novel features of the device will be particularly pointed out in the appended claims.

My invention is illustrated in the accompanying drawings forming a part of this application, in which:

Figure 1 is a plan view of the entire playing board;

Figure 2 is a perspective view of the instruments of play;

Figure 3 is an enlargement of the portion of the board contained in the dot dash rectangle labelled III in Figure 1;

Figure 4 is an enlargement of another portion of the board contained in the dot dash rectangle labelled IV in Figure 1; and

Figure 5 is a view illustrating a part of the

game where "lead rider" and "relief rider" cards are used.

In carrying out my invention, I will first describe the playing board and then the instruments of play, after which the actual playing of the game will be set forth and will include the first part of the game, Rider Round-Up, and then the second part of the game, Carrying the Mail.

The playing board indicated generally at A in Figures 1, 3 and 4, is constructed of a non-flexible material preferably made from cellulose. I do not wish to be limited to any particular material for the playing board nor to any particular size. For best results, the board should be a square of thirty inches on each side so as to fit the top of a standard-size card table. The game board A is preferably formed of three sections A¹, A² and A³, hinged together so that when the board is not in use, it may be folded along folds x and z to a size ten by thirty inches.

The playing board A has four white rectangular areas designated at B, one being placed at each corner of the board. Inasmuch as all four areas B are identical, a detailed description of one will suffice for all. Each rectangle area B, see Figures 1 and 4, has a large circle 1, colored orange, and carrying the notation Rider Round-Up as indicated at 2. Within this orange circle I show what appears to be four areas of playing card size, these areas overlapping each other. The lowest card-shaped area of the four is colored black and reference numeral 3 indicates this area. The printing on this black card-shaped area appears as Black Cantina and is indicated at 4.

35. The next card disposed directly above the black card-shaped area and partially overlapping it, is colored yellow and is indicated at 5. The words Yellow Cantina appear at 6 on the viewable portion of this area. A red card-shaped area 7 overlaps the yellow area and has the words Red Cantina appearing thereon at 8. The top card-shaped area 9 is blue in color and the words Blue Cantina are printed at 10 on this card. The four card-shaped areas, 3, 5, 7 and 9 designate the places to position certain of the playing cards hereinafter described during the first portion of the playing of the game, this part of the game being referred to as Rider-Round-Up.

Disposed around the large orange colored circle 1 are five smaller circles of a size equal to the size of playing chips used with the game, see Figure 4. Three of the smaller circles indicated at 11 are white in color, while the fourth circle of the same size is colored red as indicated at 12, and the fifth circle is colored blue and is indicated at 13. The word Cache is associated with the five circles 11, 12 and 13 and is shown at 14. White, red and blue chips will be used in the playing of the game and the player receiving these chips will

place them on the proper circles 11, 12 and 13 in accordance with the colors of the chips.

Through the central portion of the playing board, I show five separately colored rectangular panels arranged edge to edge and these comprise the central playing area of the game board, and are used during the second portion of the game which is called Carrying the Mail. Each of the five rectangular panels has a white strip extending diagonally thereacross approximately from one corner to the opposite corner of the panel and this strip 15 is designated Home Stations as shown at 16 in Figure 3. The strip is divided into sixteen equal parts shown at 15a and these parts are consecutively numbered from 1 to 16, inclusive. The five colored panels starting from the lower edge of the board A and reading consecutively in an upward direction, are as follows: the black panel C, yellow panel D, green panel E, red panel F, and the blue panel G. The central, green panel of Figure 1, is shown on an enlarged scale in Figure 3.

Associated with each of the diagonally extending white strips 15 and alongside thereof is a series or chain of thirty-eight small rectangles which are termed the Relay Trail. The thirty-eight small rectangles are indicated at 17 in Figure 3, and the words Start—38 Stations on Relay Trail, associated with the series of rectangles 17, are indicated at 18. A rider on a horse 19 indicates the direction of travel of playing pieces M called "nuggets" which will be placed on the required small rectangles 17 during the playing of the game. The words Return to Start, which are indicated at 20, are disposed adjacent to the numbered part "16" at the end of the relay trail. The player using the black colored rectangular panel C will move his nuggets along the Relay Trail 17 in the direction indicated by the horse and rider 19 and when the end of the trail is reached, which will be at the last small rectangle 17a disposed in the chain, he will move the nugget back to the start of the same trail which will be the first small rectangle 17 disposed adjacent to the division 15a numbered 1.

It will also appear from the black colored panel C, in Figure 1, that an area of the size of a playing card is shown at 21 and is labeled Home Corral as indicated at 22. At both ends of the area 21, there appears the words Black Arrow as shown at 23, and there also appears an illustration of an arrow. The purpose of the Home Corral will be made known during the description concerning the playing of the game. It should be noted that the lines dividing the strip 15 into sixteen divisions are colored black and so are likewise the chain of thirty-eight small rectangles comprising the trail 17. The small rectangles 17 have their corners contacting with each other to form the chain.

Adjacent to the black colored rectangular panel C, there is the yellow colored panel D of the same size and shape. This panel D has a diagonal white strip corresponding to the strip 15, but extending in a direction which will form an angle with the strip 15 on the panel C. Inasmuch as the diagonal strip in the yellow panel is identical to that shown in the black panel, corresponding reference numerals will be applied to similar parts. The only difference is that the lines of division in the Home Stations indicated at 15 in the yellow panel are yellow rather than black and the thirty-eight small rectangles 17 are likewise colored yellow rather

than black. Within the panel D there is a white area 24 similar to the area 21 and carrying the notation Home Corral as referred to at 25. At each end of the area 24, I provide the words "Yellow Square" and these are associated with the word "Relay" and with the showing of a yellow square. All of the portions shown in the playing card-sized area 24 are colored yellow.

The central rectangular panel is colored green and is shown at E in both Figures 1 and 3. This panel has a diagonal white strip 15 extending from the end of the white strip 15 on the yellow panel D. Inasmuch as the white strip on the green panel E is the same as the strips on the panels C and D, corresponding reference numerals will be applied to the home stations and to the thirty-eight small rectangles forming the chain 17. The green panel E has a white area 27 of the same size and shape as the areas 21 and 24 and the word Mo-Chee-La is printed on this area at 28. A second white area 29 appears on the green panel E and is disposed diagonally opposite to the area 27. The area 29 has the words Remount Station printed thereon and indicated at 30. In addition, at each end of the area 29 there appears the words Green Star as shown at 31 with an illustration of a green star associated therewith.

Two additional panels F and G are shown on the playing board A in Figure 1, and these are colored red and blue, respectively. Both of these panels have white diagonal strips 15 extending thereacross and divided into sixteen home stations and they also have a trail of thirty-eight small rectangles 17. It will be noted that the diagonal white strips 15 arranged on all five panels C to G, inclusive, form a zigzag trail which simulates the cross country trail traversed by the riders of the pony express, the trail being divided into relays. Similar parts on the panels F and G to the parts on the other panels, will be referred to by like reference numerals and the only difference from the other panels lies in the fact that the parts in the red panel F are colored red and the parts in the blue panel G are colored blue.

The red panel F has a white area 32 of the size and shape of a playing card and carrying the words Home Corral. At each end of this area appear the words Red Diamond Relay as indicated at 33 and associated with the words is an illustration of a red diamond as indicated at 34. The blue panel G has a white area 35 of the size of a playing card and with the words Home Corral printed thereon. In addition, this area has the wording Blue Moon Relay as indicated at 36 appearing at both ends of the card with a blue colored disc 37 associated therewith.

The description thus far completes the showing appearing in the corner areas B and in the five large colored panels C to G, inclusive. It will be noted that two green panels are arranged adjacent to the center green panel E and are disposed at opposite ends of this panel so as to form a row of green panels which will extend at right angles to the five differently colored panels just mentioned. One of the two additional green panels is shown at H in Figures 1 and 3, and this panel has the wording Stock Corral printed thereon as shown at 38 and associated with four colored areas indicating the overlapping of four colored playing cards. The lowermost area is shown at 39 and is colored black and also carries the notation Black Cantina

as indicated at 40. The next area 41 is colored yellow and has the words Yellow Cantina indicated at 42. The next area 43 is colored red and carries the wording Red Cantina at 44. The uppermost area 45 is colored blue and this has 5 the wording Blue Cantina indicated at 46.

Referring briefly to the other green rectangular panel J, shown in Figures 1 and 4, there appears six circles of the same size as the circles 11, 12 and 13, and the word Bonus appears at 47 in 10 association with these circles. Four of the circles are white in color and are shown at 48, while the fifth circle 49 is colored red and the sixth circle 50 is colored blue.

Both of the rectangular areas H and J have 15 orange circles 51 with the word Poke printed therein at 52. The orange circle 51 is associated with an oval 53 colored orange and within this oval appears the words Unredeemed Nuggets at 54. The ovals 53 each have two rows of numbered sections 55 carrying the numbers from 1 to 16 printed thereon consecutively (see lower part of Figure 3). White lines 56 extend tangent from each orange circle 51 to its associate oval circle 53 and connect these parts together. Between the orange circle 51 and the oval 53 I place the word Paymaster as indicated at 57.

The instruments used in the playing of the game are shown in Figure 2. A box K for initially holding the cards L is shown in perspective. It will be noted that the box is closed by two end flaps or covers and one of the covers is indicated at 58 and is provided with a circular opening 59 large enough to permit a nugget indicated at M to pass therethrough when the box is shaken. There are eighty cards used in the playing of the game and one hundred and sixty nuggets. As soon as the cards are removed from the box, the nuggets are placed therein and the box is now called a Poke for the playing of the game. 40 The nuggets are flat discs with numbers appearing on both faces. There are thirty-two black nuggets, thirty-two yellow nuggets, and thirty-two of each of the green, red and blue nuggets. The five groups of differently colored nuggets of thirty-two each, total the one hundred sixty nuggets above referred to. There are sixteen cards to each suit numbered one to sixteen and there are five differently colored suits.

There are two hundred poker chips N and these are divided into one hundred and twenty white poker chips, forty red poker chips, and forty blue poker chips. The cards, poker chips, nuggets and poke K are called the instruments of play and are used by the players in connection with the playing of the game on the board A.

In the playing of the game the first part of the game called Rider Round-Up is played first. Each player is provided with thirty white chips worth \$5.00 each; ten red chips worth \$10.00 each and ten blue chips worth \$15.00 each. Each player then shakes the poke K to eject one nugget M from the opening 59. The player receiving the highest nugget number regardless of color becomes the dealer for the game as well as its paymaster. Each player occupies one side of the playing board and the white area B directly to each player's right becomes his own area. The cards are shuffled and dealt to the players and to the Stock Corral 38 shown in Figure 3 until each receives sixteen cards.

The playing of the first part of the game, "Rider Round-Up," begins with the player to the left of the dealer and he removes the top card from the sixteen cards placed on the Blue Can-

tiny of Stock Corral 38. Prior to taking the card, each player has arranged his sixteen cards in accordance with the five colored suits, these suits being designated by the different colors of the cards and also by the fact that at each end of each card the insignia corresponding to the card color is shown. For example, the sixteen black cards each show the black arrow at both ends of the cards, the sixteen yellow cards will show the yellow squares, the sixteen green cards will show the green star, the sixteen red cards will show the red diamond, and the sixteen blue cards will show the blue circle.

The first player upon removing the uppermost card of the sixteen cards which have been placed face down on the Blue Cantina of Stock Corral 38 checks this card with those contained in his hand. The purpose of this part of the game is to permit the player to build up the highest suit he holds in his hand which is termed Selected Suit. The green cards cannot be regarded as a selected suit. If the card removed by the first player from the Stock Corral 38 is one that he would like to retain, he must discard one of his own cards to Remount Station 29. If he holds any green cards, these are the first ones he should discard, although this is not compulsory. Should the player upon removing a card from the Stock Corral, not desire to retain it, he may discard it and such card is placed upon the Remount Station 29 in the green panel E, see Figures 2 and 3.

Each player takes his turn in a clockwise direction until all four players have had an opportunity to remove a card from the Stock Corral and either retain the card while discarding one of his own or discard the card withdrawn and lay it face down directly on the area termed Remount Station. It will be seen that inasmuch as there are sixteen cards in the Stock Corral, the first phase of the game will consist of four plays of the players, each one removing a card from the Stock Corral in his turn until all of the cards are removed. There will be sixteen cards on the area 29 termed Remount Station at the end of round one comprising this first series of four plays for each player.

Each player accepting a card (Rider) from the Stock Corral 38 and discarding a card (Rider) from his hand into Remount Station 29, must pay Bonus 47 one white chip from player's Cache 14. The Bonus is a depository consisting of the circles 48, 49 and 50, for the players' chips when such becomes mandatory during the playing of the game.

55 After finishing round one, the cards are then removed from Remount Station by the dealer and may be shuffled again and placed on the Red Cantina area 38 designated Stock Corral. The players then repeat the performance of each removing one card and either retaining this card and discarding one from the hand, or discarding the drawn card and placing it on Remount Station in the same manner as was previously done when the sixteen cards were played from the Blue

60 Cantina of the Stock Corral. This may be termed round two. The play continues in this manner for two more rounds. The cards are placed in the Yellow Cantina of the Stock Corral for round three and are placed on the Black Cantina of the Stock Corral 38 for round four. After round four, each player has the best set of cards so far as he is concerned that it is possible for him to obtain from the original sixteen cards dealt him and the 75 substitutions which he has been able to make in

his hand during the four rounds from the Stock Corral 38. The portion of the game called Rider Round-Up is now finished.

Through the playing of the first part of the game called Rider Round-Up, each player keeps his chips on the circles 11, 12 and 13 termed Cache, placing the colored chips on similarly colored circles. The white area B, see Figure 4, with the large orange colored circle labelled Rider Round-Up is also used in playing the first part of the game and contains each player's four differently colored Cantinas 3, 5, 7 and 9. The Blue Cantina 9 is the depository for the player's selected suit immediately following the first deal and during the first drawing from the Remount Station 29, already mentioned.

The player moves his selected suit to the Red Cantina 7, immediately following the first round and the reshuffling of the sixteen cards taken from the Remount Station by the dealer and placed on the Red Cantina 43 in the Stock Corral 38. In like manner the player moves his selected suit to the Yellow Cantina 5 and then to the Black Cantina 3, during the third and fourth rounds or drawings, the dealer transferring the sixteen cards from the Remount Station 29 to the Yellow and Black Cantinas 41 and 39, respectively, of the Stock Corral 38 at the start of each of the third and fourth drawings. The Stock Corral 38 is designed for receiving the fifth hand cantina of sixteen cards and it is from these cards that the four players select their Rider cards during the first, second, third and fourth rounds or drawings just mentioned.

If a player during the first part of the game called Rider Round-Up, is fortunate enough to have or collect sixteen cards of the same suit, his selected suit will represent sixteen Riders, one for each card, and the cards will have identical symbols and will all be of the same color and numbered in sequence from "1" through "16." It will be apparent that a player will usually receive far less than a full suit of sixteen cards during the dealing of the cards. Therefore, his selected suit will be the one having the most cards of the same color. The players before playing the second part of the game termed Carrying the Mail, may reseat themselves in order to be nearer the particular large panel C, D, F or G that corresponds with their Selected suit.

The Green Star Relay suit of sixteen consecutively numbered cards or Riders does not form one of the selected suits. If the player is dealt any of these cards, he may discard them to the Remount Station 29 during the playing of the Rider Round-Up or first part of the game. He can only discard these green cards one at a time and only when a card is picked from the Stock Corral 38 and is retained by the player. Should a green card be picked from the Stock Corral by a player during his turn, he can immediately discard this card by transferring it to Remount Station.

The Green Star Relay panel E is not used as a playing area for any individual player for the second portion of the game called Carrying the Mail, until a player has activated all sixteen Riders (cards) in his hand and placed them either in the Home Corral located in the panel of his choosing or sold them to his opponents as hereinafter set forth. The selected suit of each player determines the rectangular panel of C, D, F, or G, he will choose because this panel corresponds in color and name to the player's selected suit. When a player has played all sixteen of his cards, he can

play in the Green Star Relay trail 17 or participate in a play as directed by a Rider (card) drawn from the Remount Station 29 and placed on Mo-Chee-La 28, hereinafter explained.

At the end of the four rounds of Rider Round-Up, the players turn their selected suits face up and place them on their white areas B. Should two players select the same suit, the one having the greater number of cards of the suit in question, may purchase the same suit from the other player and pay from his Cache 14, five dollars in chips for each card thus purchased, the payment being made to Bonus 41. The chips thus transferred are stacked on the colored circles 48, 49 and 50. The player purchasing the cards or Riders, gives an equal number of his cards or Riders to the other player so that each player continues to have sixteen cards.

The dealer in the first part of the game becomes the paymaster during the playing of the second portion of the game entitled, Carrying the Mail and is the first one to play. He shakes a nugget M from the poke K and checks the color and number on the nugget and then looks at his own sixteen cards to determine whether he has a card (Rider) corresponding in color and number to that of the nugget. If the color of the nugget corresponds to his selected suit and if the number on the nugget is the same as one of his numbered cards in the selected suit, he plays this Lead Rider card into the Home Corral area in the rectangular panel corresponding to his selected suit. For example, if the paymaster's selected suit is Red Diamond and he throws a red nugget numbered "1," and he happens to have the number "1" card of this suit, he places this card on the Home Corral 32 in the red rectangular panel F in Figure 1 where it remains. This card remains out of play from then on to the end of the game.

The red nugget is then taken by the paymaster and moved along the trail 17 in the panel F, a distance corresponding to the data appearing in the first line on the card that is transferred to Home Corral. Figure 5 shows the red card L, numbered "1" and the first line states, "Advance 5 Stations." The paymaster therefore moves the red nugget five red steps along the relay trail 17 and in the direction indicated by the horse and rider 19 associated with this red Relay Trail. When it has been determined that the nugget called, corresponds to the number and color of the selected suit in the paymaster's hand, as just explained, each of the other three players pays to the paymaster's Cache 14, the equivalent of \$5.00 in chips (one white chip). The same would hold true for any player whose turn it happened to be.

The card just played is considered a Lead Rider. Any one of the eighty cards held in the four players' hands or forming a part of the "fifth" hand in Remount Station 29 may be termed a Lead Rider. Such cards are activated only when a nugget of the same color and number is shaken from the poke K and called by the paymaster. Once the card has been played into the Home Corral, it is considered to be "out-of-play" and its numerical identity relates only to the nugget placed in position on the Relay Trail.

When the nugget shaken from the poke by the paymaster, corresponds to the color of an opponent's selected suit, but the numbered nugget corresponds to the color and number of a card in paymaster's hand, the opponent must pay the player's Cache 14, fifteen dollars in chips. Before play is resumed, the opponent may ask to pur-

chase the card (Rider) from the paymaster at a price of \$15.00 in chips. If the request is accepted by the paymaster and the amount paid, the opponent may possess the card (Rider) and related nugget and play them as though the Rider was originally held in opponent's hand. If the request is denied by the paymaster, he must pay \$15.00 in chips from his Cache 14 to the Bonus 47. The reverse is true if the paymaster throws a nugget whose color and number are similar to a card of an opponent who has selected the same suit. If the nugget called by the paymaster corresponds in no respect to any of the player's Selected suit riders in player's hand or that of the opponent, it is to be presumed that the missing Rider (card) is in the Remount Station 29 containing the "fifth" hand. The paymaster then places the player's nugget in the oval panel 53 marked Unredeemed Nuggets and the player pays \$15.00 from his Cache 14 to Bonus 47. The oval panel has the two rows, each containing sixteen squares consecutively numbered from "1" through "16." The number appearing on the nugget determines its place on a similarly numbered square. Since there are two oval panels 53 and four rows of squares 55, there will be sufficient spaces provided for the unredeemed nuggets. Thus far the explanation of the game has set forth the different situations that might arise when the paymaster is the first to play. The same situation could arise for different players as each takes his turn.

The players take turns in playing and the play proceeds in a clockwise manner around the table. The dealer who is now the paymaster, shakes out one nugget at a time for each player. Each player when playing a card (Rider) from his hand, moves the nugget, shaken from the Poke K by the paymaster, the number of spaces along his relay trail 17 as indicated on the card and then places the card in the Home Corral of the panel C, D, F or G, chosen by him and agreeing in color with his selected suit.

As each new nugget is played by the players in taking their turns, the new nugget takes the place of the former one on the player's relay trail 17, and the former nugget is then placed in a Home Station division 15a of the player having a number corresponding to the number on the nugget. The new nugget is advanced along the relay trail from the position of the old nugget, a distance corresponding to the information contained on the first line of the card corresponding in color and number to the new nugget. The new nugget occupies the advanced position thus attained. It will be seen that the Bonus 47 will be gradually built up in the number of differently colored chips received as the players pay into it according to the rules of the game. Any player completing the traversing of the thirty-eight stations on his relay trail with nuggets, starts at the beginning of his same relay trail again and is entitled to receive all of the chips accumulated by the Bonus. In this way there is a continual incentive in the game for each player to traverse his relay trail as rapidly and as often as possible.

Each of the eighty riders (cards) is represented by the name of an actual pony express rider. The name of the rider and all text appearing on the card is in a color corresponding to that of the symbol of the particular suit to which the rider belongs. For example, the card L shown in Figure 5 has the red diamond symbol 60 and therefore all printing or text on this card will be in red. The cards (Riders) are divided into five

groups of sixteen cards each, called suits. The individual cards (Riders) of each suit are consecutively numbered from "1" through "16" and are identified by color, and symbol and refer to the relay panels C to G, inclusive.

There are two kinds of Riders: "Lead" and "Relief." All eighty cards are considered "Lead" Riders. Each Lead Rider (card) has information which appears in smaller type opposite the symbol on the card. The nugget of the player is played on the relay trail 17 in accordance with the information given on the card. The Lead Rider card L in Figure 5 has the notation opposite the symbol 60, reading "Advance 5 Stations." The player advances the nugget five spaces along his relay trail 17 when he is playing this card. The color and number of the nugget determines the card to be played.

A Relief Rider is any one of the same eighty cards not held in a player's hand, the "fifth" hand and Remount Station being excepted, provided that the number and color of the nugget called is not the same as a card of similar color and number in any player's hand and provided that the color and number of the nugget corresponds to that of a "counter-part" number appearing on one or all three possible Lead Riders of the same selected suit; i. e., same color as the nugget and held by one or more players. For example, a red nugget numbered "1" may be called by the paymaster and it is found that an identical nugget in color and number has been previously called and its related Lead Rider (card) has been activated. It should be remembered there are one hundred sixty nuggets so there will be two identical nuggets of color and number for each of the eighty cards. Since the Lead Rider (card) L in Figure 1, has been played into the proper Home Corral, the second identical nugget shaken from the Poke K and called, must represent a Relief Rider card.

As in the case of a Lead Rider (card), the Relief Rider card may be activated only when a related nugget is called by the paymaster. The "counter-part" numbers on the Lead Rider card L in Figure 5 which has been played are "5," "9" and "13," and the player as well as his opponents consult their hands to determine whether they have Lead Rider cards of the same suit and numbered "5," "9" or "13." In actual play, the possession of the related nugget is determined by the player or opponent who holds the lowest denomination Lead Rider card of the three listed. Assume that Lead Rider card "5" has been previously played and an opponent holds Lead Rider card "9" which represents the next lowest "counter-part" number.

The opponent takes possession of the nugget and plays it according to the text on his card numbered "9." Figure 5 illustrates graphically the actuation of a Relief Rider card in place of the activated Lead Rider. The play is made in accordance with the "counter-part" numbered "1" appearing on Relief Rider card numbered "9." Card numbered "9" is not actually played by opponent into his Home Corral, but it remains in his hand until activated as a Lead Rider. If the relief rider of player's selected suit is in his own hand, each opponent must pay player's Cache 14, the equivalent of \$5.00 in chips (one white chip). The Relief Rider card held by the player must be the lowest number on the Lead Rider card, otherwise the play may revert to an opponent who does have the lowest numbered Relief Rider card. The nugget is played after

consulting the text opposite the "counter-part" number on the card corresponding to the Lead Rider card number. The new nugget is substituted for the former one and if a move along the relay trail 17 is indicated, this is done, otherwise only a substitution of nuggets is made. The former nugget is placed in the player's Home Station in the division 15a corresponding to the numbers on the nugget.

If the relief rider card of opponent's selected suit is in the player's hand as determined by the color and number of the called nugget, opponent must pay player's Cache 14 the equivalent of \$15.00 in chips. Before the play is resumed, the opponent may request the purchase of the nugget from the player at the price of \$15.00. If the request is accepted, the opponent may possess the nugget, but may not play it until the full status of the Relief Rider card has been determined. If the request is denied, the player may retain the nugget, but must pay \$15.00 from his Cache 14 to Bonus 47, and cannot play the nugget until the full status of the Relief Rider card is determined. Should a player other than the original player or opponent qualify as having the desired Relief Rider card, then the player or opponent must pay the player involved, \$15.00.

When it is has been determined that the nugget called, corresponds to the number and color of a player's nugget previously placed in unredeemed nugget area 53, the player pays Bonus 47, fifteen dollars in chips and the paymaster places it in the unredeemed nugget area. This means that the Relief Rider card of the player's selected suit is in Remount Station 29.

Should a green nugget be shaken from the poke K, and the number corresponds to the number of a green card held by a player whose turn it is to play, the player plays the nugget and card like any one of his selected suit and each player pays five dollars in chips to Bonus 47. The player then places the nugget on his own relay trail 17 and substitutes it for the former nugget on his trail. The former nugget is placed on Home Station 15. If an opponent has the green card with the same number as appears on the green nugget, the play is the same as if the nugget called corresponded in color and number to the selected suit of the opponent and the opponent had a card of the same number as the nugget in the selected suit. Should a green nugget be thrown and no player has a corresponding card, such nugget is placed in the oval 53 of unredeemed nuggets. When a called green nugget corresponds to a number of a green nugget previously placed in unredeemed nuggets, each player pays Bonus 47 the equivalent of \$5.00 in chips and the green nugget is placed in the unredeemed nugget area.

Each time a player has succeeded in accumulating four nuggets in one of his Home Stations having identical numbers, the player may call out "Bonus" and is entitled to receive into his player's Cache 14, all of the chips that have accumulated in Bonus 47 during previous plays. When a nugget is called whose Rider card is not held by any player, it must be presumed that the particular card is in Remount Station 29. The nugget is therefore placed in unredeemed nuggets area 53 and each player must pay to the Bonus 47, the equivalent of five dollars in chips.

When a green nugget is called that corresponds to the number of the green nugget previously placed in position on player's relay trail 17 or within player's Home Station 15, the same procedure takes place as that described for Relief

Rider of player's selected suit in player's hand or Relief Rider of opponent's selected suit in player's hand.

After a player has finished activating all sixteen of his cards, he can play in the green panel E. When a nugget is called which represents a player or players eligible to participate in the play of the green star relay trail 17 in panel E, he draws the top Rider card from Remount Station 29. The Rider card thus drawn may relate to one or two nuggets formerly placed in the unredeemed nugget areas 53. The nugget or nuggets thus redeemed are placed in their respective positions and the player may withdraw the equivalent of \$15.00 in chips for each nugget from Bonus 47 and place them in his Cache 14. The card drawn from Remount Station 29 is placed on the area 27, designated Mo-Chee-La.

In the event that no previous green star nugget has been placed on the green star relay trail, then the player participating in the green star relay may advance his own nugget the number of squares as directed by the text opposite the "counter-part" number of the Remount Station Rider card drawn, and the card is placed in Mo-Chee-La. If there is a nugget on the green relay trail 17, this nugget is advanced the number of squares as directed by the text opposite the "counter-part" number of the Remount Station Rider card drawn. The card thus played is placed on Mo-Chee-La.

If a Rider card drawn from Remount Station 29 is the same as the player's selected suit, each opponent must pay to the player's Cache 14, the equivalent of \$5.00 in chips. The player then takes the nugget called and places it on his own relay trail 17 in substitution of nugget already on the trail and removes the substituted nugget to the Home Station division corresponding to the number on the nugget thus removed. The player also consults the Rider card thus drawn from Remount Station and removes any nuggets of the same color and number as the card that might be in the unredeemed nugget areas 53. The player receives \$15.00 from Bonus for each nugget thus redeemed. The redeemed nuggets are placed on player's relay trail and advanced the number of squares indicated by the text opposite the "counter-part" number on the card. If two related nuggets are redeemed, the second one is advanced on player's relay trail 17 an equal number of squares from the first nugget, and the first one is transferred to Home Station. The drawn card is transferred to Mo-Chee-La. If a green nugget is called which relates to a green star Rider card already played as a Lead Rider, the player may participate in the normal manner by drawing the top-most Rider card from the Remount Station 29 and proceed as usual.

If the Rider card drawn from Remount Station is that of opponent's selected suit, opponent must pay to the player's Cache 14, the equivalent of \$15.00 in chips. The opponent then plays the nugget on the green relay trail 17 and participates as though he were playing a Lead Rider card on his own relay trail. The opponent consults the drawn Rider card and removes related nugget or nuggets from the unredeemed nugget areas 53, receiving \$15.00 in chips from the Bonus 47 for each nugget thus redeemed. The redeemed nugget is placed on opponent's relay trail and advanced the number of squares as directed by the text shown on the card opposite the counter-part number of the

Remount Station Rider card drawn. If two nuggets are thus redeemed, the second one is advanced a like number of steps as the first along the relay trail, and the first is transferred to the Home Station. The drawn Remount Station card is then transferred to Mo-Chee-La.

When a nugget is called which relates to a player participating in the green star relay E and the player draws the last Rider card from Remount Station 29, the usual procedure of clearing the player or opponent, activating any unredeemed nuggets, paying into bonus the necessary chips is carried out and then the card is placed in Mo-Chee-La. This signals the end of the game and the player receives the remaining chips from Bonus 47. The winner of the game is the one having the most chips.

I claim:

1. In a game board; a plurality of differently colored rectangular panels arranged edge to edge in a row; each panel having a trail extending from one corner of the panel to the diagonally opposite corner; these trails being composed of a plurality of adjacent rectangles touching each other only at their corners; the trails of adjacent panels being inclined in opposite directions and touching each other to form a combined trail which is zig-zag in shape; and playing pieces adapted to be moved along the trails.

2. In a game board; a plurality of differently colored rectangular panels arranged edge to edge in a row; each panel having a trail extending from one corner of the panel to the diagonally opposite corner; these trails being composed of a plurality of adjacent rectangles touching each other only at their corners; the trails of adjacent panels being inclined in opposite directions and touching each other to form a combined trail which is zig-zag in shape; playing pieces adapted to be moved along the trails; and each panel also having a plurality of numbered spaces arranged in a line that parallels the trail; the numbered spaces being designed to receive the playing pieces.

3. In a game board; a plurality of differently colored rectangular panels arranged edge to edge in a row; each panel having a trail extending from one corner of the panel to the diagonally opposite corner; these trails being composed of a plurality of adjacent rectangles touching each other only at their corners; the trails of adjacent panels being inclined in opposite directions and touching each other to form a combined trail which is zig-zag in shape; playing pieces adapted to be moved along the trails; each panel also having a plurality of numbered spaces arranged in a line that parallels the trail; the numbered spaces being designed to receive the playing pieces; and each panel with the exception of one panel further having playing card-shaped areas thereon designated "Home Corral";

the panel not having such an area being provided with two playing card-shaped areas, one being designated "Remount Station" and the other being designated "Mo-Chee-La."

4. In a rectangular game board; a plurality of identical corner areas, one being arranged at each corner of the board; each area having a plurality of playing card-shaped portions of different colors arranged in overlapping relation; a plurality of cards having the same colors as the colored portions, each color representing a different suit; the colored portions being designed to receive the player's selected suit; five differently colored rectangular panels arranged one above the other in a vertical column that extends between the corner areas; the colors of the panels with the exception of one corresponding to the colors of the playing card-shaped portions in the said identical areas disposed at the corners of the board; each panel having a trail extending from one corner of the panel to the diagonally opposite corner; these trails being composed of a plurality of adjacent rectangles touching each other only at their corners; the trails of adjacent panels being inclined in opposite directions and touching each other to form a combined trail which is zig-zag in shape; playing pieces adapted to be moved along the trails; a pair of additional panels placed on opposite sides of the central panel in the vertical column and positioned between the corner areas; each one of the pair of the additional panels having an oval-shaped area with two rows of numbered spaces; said playing pieces having numbers and adapted to be placed in the spaces having corresponding numbers.

ROBERT L. ROBBINS, JR.
